ATTORNEYS.

UNITED STATES PATENT OFFICE.

LUTIE KERN, OF LAWRENCE, KANSAS.

AUXILIARY HEATING DEVICE.

Application filed April 9, 1928. Serial No. 263,421.

My invention relates to smoke abaters, and more particularly to devices of that character for use with furnaces in dwelling houses and the like, the principal objects of

5 the invention being to conserve the heat of gases passing from furnace to the chimney, to utilize the gases for heating purposes, and to distribute the heat rescued from the gases. Further objects are to promote the 10 efficiency of fuel and gas combustion, and to reduce the proportion of unconsumed gases issuing from the chimney into the atmosphere.

15 In accomplishing these and other objects of my invention, I have provided improved details of structure, the preferred forms of which are illustrated in the accompanying drawings, wherein:

20 Fig. 1 is a perspective view of my invention installed in operable relation with a furnace and chimney.

Fig. 2 is a detail perspective view of the device, a part being broken away to better illustrate other parts.

25 Fig. 3 is an end view of the device illustrating one end wall and a connector pipe and elbows removed.

Fig. 4 is a central sectional view of a controlling damper.

30 Fig. 5 is a fragmentary sectional view on the line 5—5, Fig. 2 illustrating the joint of a removable end wall.

Referring in detail to the drawings:

1 designates a basement in which is located a furnace of usual construction having pipes 3 for heated air leading to a floor 4 supported by joists 5. A smoke pipe section 6 is connected into the furnace, and a similar smoke pipe section 7 is connected 40 into a chimney 8. Ordinarily the sections 6 and 7 of smoke pipe are continuous for conducting smoke from the furnace to the chimney. I provide, however, a heat conserving device generally designated 9, and interpose it in series with the smoke pipes 6 and 7. The heat conserving device includes a rectangular housing 10, in which is positioned a meandering smoke conduit 11 having opposite ends 12 and 13 connected with the furnace pipe section 6 and the chimney pipe section 7 respectively, as later described. The housing comprises similar side walls 14 and 15, end walls 16 and 17 removably secured to the side walls, a bottom 18, a removable cover or top 19 adapted for outlet of heated air and having an opening 20 preferably in

the side wall 15 to admit air for circulation over the smoke conduit, all of which will be more particularly described.

The housing is supported from the floor 60 of the basement by legs 21 fixed to the side walls by means such as belts 22 and socket members 23 having vertical openings 24 in which the legs are slidably, the legs being fixed in selected position by thumb screws 65 25 extending through threaded openings 26 in the socket members into engagement with the legs. The socket members are provided with stabilizing foot portions 27 having openings 28 to receive fastening means for 70 fixing the socket members to the floor.

Fixed between the side walls 14 and 15 and in spaced relation with the end walls 16 and 17, are similar supporting brackets 29 and 30, preferably castings, each having 75 vertical flanges 31 whereby it is secured to the side walls as by the bolts 22 which secure the legs to the side walls and being provided with a large central rectangular opening 32 for a purpose later to be described. The opening leaves relatively narrow side portions or wings 33 and 34 which are provided with vertical series of flue-receiving openings, 35 and 36, the series of one wing being staggered with reference to the 80 series of the other wing, the staggered relation being particularly illustrated in Fig. 3.

The openings 35 of one bracket are also staggered with relation to the openings 35 85 of the other bracket, and supported in corresponding openings of the two brackets, and extending longitudinally in the housing, are sections 37 of the smoke conduit 11, the ends of the sections projecting through 90 the openings of the brackets sufficiently to receive pipe fittings such as elbows. The sections 37 are provided with lugs 38 near their ends which are adapted to pass through notches 39 in the upper margins of 100 the bracket openings, upon inserting the sections in the brackets. A partial turn of a section, the lugs thereof being within the inner walls of the brackets, will cause the lugs to engage the walls and prevent end- 105 wise movement of the section.

The conduit sections 37 are connected at their adjacent ends by elbows 40 and transverse end pipes 41, with exceptions as noted below. The section positioned in the topmost of the openings 36 is especially designated 42, and is provided at one end with a

manifold pipe fitting 43, communicating with the upper transverse pipe 41, and also communicating with an extension flue member 44 aligning with the section and projecting through an opening 45 in the end wall 16, the remote end of said section being connected with the outlet end 13 of the conduit which extends through an opening 46 in the opposite end wall 17 of the housing. The inner end of the lowermost of the sections 37, which is positioned in the lower of the openings 36 of the side portions of the brackets, comprises the inlet end 12 of the meandering conduit, and extends through an opening 47 of the end wall 16 in vertical alignment with the opening 46.

The inlet 12 of the conduit is connected with an upwardly directed elbow 48, and therethrough by a pipe 49 with a box or valve chamber 50 presently described in detail, and the section extension flue 44 is connected by a pipe 51 with the chamber. The furnace pipe section 6 extends into said chamber, and a valve gate 52 is vertically slidable therein for alternatively closing one or another of the inlet elements 12 and 44, and directing smoke from the furnace into the section 42, or into the tortuous course having inlet through the conduit end 12.

The end wall 54 of the valve chamber is provided with vertically aligned ports 55 and 56 and pipe receiving projections 57 and 58 fixed in the ports, the direct flow flue extension 44 being connected to the projection 57 and therefore communicating through the upper port 55 with the chamber, while the tortuous-course inlet 12 is connected to the projection 58 and communicates with the chamber through the port 56. Guide flanges 59 fixed to the similar side walls 60 of the chamber are spaced from the end wall 54 to produce therewith grooves 61 in which the valve gate 52 is slidable, the valve being operably supported by arms 62 extending slidably through the top 63 of the chamber and connected by a yoke having an eye 64 for attachment of a chain 65 whereby remote control of the valve is provided. As illustrated in Fig. 4, the valve gate when in lower position closes the port 56 and in upper position closes the port 55. The other end wall 65 of the chamber is provided with a port 66 horizontally aligned with the direct-flow port 55, and a projection 67 for connection of the chamber with the furnace smoke pipe section 6 is provided peripherally of the port, the smoke entering the chamber through this pipe section and port, and the course of the smoke through the housing conduit sections being controlled by the valve gate which permits smoke to pass into one or another of the inlet members 12 or 44. A sliding plate 68 is movable on flanges 69 on the lower edges of the

chamber walls to open or close the bottom of the chamber for clean-out purposes.

The heat received by the conduit sections from gases of smoke passing therethrough, is utilized by provision of the air inlet 20 in the side wall of the housing adjacent the bottom, and the heated air outlet in the cover member. A cold air conduit 70 is preferably connected into the air inlet, and leads from a register 71 in the floor above the furnace whereby air may be drawn from the area to be warmed and circulated through the supplementary heater for return to said area through a conduit 72 connected into the heated air outlet and leading to a register 73 in the floor.

Convenient access to the interior of the housing for cleaning the pipe sections, is provided for by the removable character of the end walls of the housing, which specifically are provided with flanges 74 on their vertical edges for receiving the vertical edges of the side walls, the lower edges of the end walls being retained in position by engagement with flanges 75 of the bottom member 18. Hooks 76 attached to the side walls may be latched over screws 77 fixed in the flanges 73 to securely join the end and side walls. The stability of the housing is further enhanced by the means for removably supporting the cover, said cover having a peripheral flange 78 split at the corners whereby the end portions of the flange may extend within the end walls of the housing while the side portions lie along the outer faces of the side walls.

Assuming a heat conserver installed according to the description given above, with a pipe leading into the valve chamber from the furnace and a pipe leading from the housing to the chimney, the normal operation of the device provides for the closing of the upper housing-inlet port, so that the smoke from the furnace will travel over the tortuous course through the housing, whereby the departing gases are restrained sufficiently for promoting consumption before discharge into the chimney, and a substantial area of conduit-section is traversed by the hot gases within the housing, and the heat thereof largely extracted by the conduit-sections and the cold air passing therover through the housing. The depending connection between the valve chamber and the inlet 12 conduces to the restraining effect on the gases, while the regularly upwardly inclined course provided by the sections of pipe positioned in staggered bracket openings permit the gases to flow by reason of their natural levity through the housing-contained conduit sections. The air admitted into the housing circulates around the flues or conduit-sections, passing also through the openings of the bracket plates into the ends of the housing and so into

contact with the elbows and transverse pipes to collect heat therefrom.

When desirable, the lower port of the chamber may be closed, and the departing products of combustion directed through the upper port into the direct-flow housing inlet 44 for passage by a direct horizontal or slightly upwardly inclining path through the housing to the chimney. Such disposition of the sliding valve in the valve chamber may be made when a particularly free draft is desired, for example when starting or reviving a fire. Attention is called to the structure whereby the topmost conduit section constitutes the final section through which the smoke passes in either position of the valve gate, so that the smoke flow is shunted from the direct entry to the said section to the tortuous course but reaches the said section for final egress in the chimney.

When access to the housing is desired, the pipes connecting the housing to the valve chamber and the chimney are removed, and the end walls are removed from the housing. Removal of the end walls is facilitated by the provision of easily releasable hooks engaging the end walls with the side walls, the seating of the end walls in the flanges of the bottom member, and the positioning of the end flanges of the cover within the end walls. The interior of the housing being thus exposed, the elbows and transverse pipes may be removed from their connection with the longitudinal sections, the lower end assembly being illustrated as disconnected in Fig. 3; since the sections are straight and may thus be opened at each end, a swab may be passed therethrough for cleaning them.

Attention is further called to the fact that the smoke passes through the housing under the conditions requiring a particularly free draft, and at no time is a supplemental control for smoke flues required or desirable, the control being confined to the diversion into one or the other of the housing courses, and to the usual ash-pit draft damper for inlet of air. The unobstructed passage of gases from the furnace provides for the burning of all conducted gases in the flues, whereby a relatively negligible amount of substances such as soot is deposited on the inner walls of the conduits or passes into the chimney. The absence of soot in the chimney also reduces greatly and practically eliminates the hazard of fire from such source. The retarding of rate of flow of burning and burned substances by diversion into the tortuous conduit tends to retain the substances in the furnace for complete combustion, whereby the furnace is heated to a greater degree proportionately to fuel used. The interior of the housing, that is the air therein, is heated when the slightest combustion is occurring in the furnace and circulation of air in the

area served is therefore set up substantially coincidentally with the starting of a fire. While the air-circulating structure is illustrated as comprising pipes leading from the floor of the area above the basement, and returning thereto, the cold air supply may be from any desired source, and the heated air may be passed into any desired channels.

What I claim and desire to secure by Letters Patent is:

1. In a smoke abater, an enclosed chamber, removable end walls for the chamber, spaced brackets within the chamber, a pair of parallel series of inclining flues supported in the brackets, end flues connecting pairs of flues for providing a continuous meandering flue, and means for controlling flow through the flue.

2. In a smoke abater, an enclosed chamber, removable end walls for the chamber, spaced brackets within the chamber, a direct conduit extending through the end walls and supported by the brackets, a pair of parallel series of reversely inclining flues supported in the brackets, end flues connecting the flues, constituting a continuous inclined meandering flue, and means for directing flow selectively through the direct conduit or meandering flue.

3. In combination with a furnace and chimney, an enclosed chamber, a direct conduit communicating with the furnace and chimney, an inclining tortuous conduit in said chamber in shunt with the direct conduit, and means for controlling flow through said conduits including a valve housing having an inlet from the furnace, a pair of outlets connected respectively with the direct conduit and the tortuous conduit, and a valve for controlling flow through said cutlets.

4. In combination with a furnace and chimney, an enclosed chamber, a direct conduit through said chamber communicating with the furnace and chimney, an inclining tortuous conduit in shunt with the direct conduit, and means for controlling flow through said conduits, including a valve housing having an inlet from the furnace and a pair of outlets connected respectively with the direct conduit and the tortuous conduit, a valve for controlling flow through said outlets, and a removable clean-out bottom for said housing.

5. In a smoke abater, an enclosed chamber, removable end walls for the chamber, spaced brackets within the chamber, a direct conduit extending through the end walls and supported by the brackets, a pair of series of reversely inclining flues supported in the brackets, removable end fittings for the paired series of flues for constituting a continuous inclined tortuous conduit, and means for selectively directing flow through the conduits.

6. In a smoke abater, an enclosed chamber, removable end walls for the chamber, a cold air inlet near the bottom of the chamber, a warm air outlet near the top of the chamber, spaced brackets within the chamber, a direct conduit extending through the end walls and supported by the brackets, a tortuous conduit in shunt with the direct conduit and supported by the brackets, and valve means for controlling flow through said conduits.
7. In an auxiliary heating device for interposing a smoke pipe between a furnace and a chimney, a housing having an air inlet and an air outlet, a meandering smoke conduit in the housing comprising a plurality of communicating sections, one of said sections being connected with the chimney-connected portion of said smoke pipe, and comprising a direct flow section, an upwardly directed pipe leading from another of said sections toward the furnace-connected portion of said smoke pipe for normal inlet of smoke to the conduit, a supplemental smoke inlet connected into said direct flow section, a valve chamber connected into said furnace-connected portion of the smoke pipe and having a port in its wall opposite to the furnace connection to receive said supplemental smoke inlet and a port vertically spaced therefrom to receive said normal inlet to the conduit, and a valve in
- the chamber alternately closing said ports to permit smoke to pass from the furnace through the meandering conduit or the direct flow section. 35
8. In an auxiliary heating device for interposing between a furnace and a chimney, a housing having an air inlet, an air outlet, a meandering smoke conduit in the housing 40 comprising a plurality of communicating sections, one of said sections being connected with the chimney and comprising a direct flow section, an upwardly directed pipe leading from another of said sections toward the furnace, a valve chamber communicating with the furnace, means connecting the chamber with said direct flow section and with the upwardly directed pipe, and a valve in the chamber controlling flow through said 45 means and said upwardly directed pipe.
9. In a smoke abater, an enclosed chamber including removable end members having conduit receiving openings, spaced brackets within the chamber, a direct conduit, a conduit in shunt with the direct conduit having ends mounted in said openings and a tortuous portion comprising a pair of vertical 55 series of inclining flues supported by the brackets within the chamber and end flues connecting pairs of flues, and means for controlling flow through said conduits. 60

In testimony whereof I affix my signature.
LUTIE KERN.
